UNITED STATES PATENT OFFICE

155,005

DESIGN FOR A COMBINED PERFUME BOTTLE AND RECEPTACLE

Elizabeth N. Graham, New York, N. Y.

Application December 2, 1947, Serial No. 142,914

Term of patent 14 years

(Cl. D58—9)

To all whom it may concern:

Be it known that I, Elizabeth N. Graham, a citizen of the United States of America, residing in New York city, county of New York, and State of New York, have invented a new, original, and ornamental Design for a Combined Perfume Bottle and Receptacle, of which the following is a specification, reference being had to the accompanying drawing, forming part thereof, wherein,

The dominant features of my design are the portions shown in full lines.

I claim:

The ornamental design for a combined perfume bottle and receptacle, substantially as shown and described.

ELIZABETH N. GRAHAM.
